INVENTOR.
Davis Marinsky
BY *Arnold E. Thompson*
ATTORNEY

UNITED STATES PATENT OFFICE

DAVIS MARINSKY, OF NEW YORK, N. Y.

BUCKLE

Application filed September 4, 1930. Serial No. 479,681.

This invention relates to belt buckles and particularly to devices of this class wherein the body portion of the buckle is composed of separate relatively movable parts to form a storage chamber or compartment within 5 and between said parts, and the object of the invention is to provide a buckle of the class specified consisting of a substantially box-shaped buckle casing and coupling plate pivotally mounted on and adapted to be arranged within the compartment of said casing, and a cover member movably supported in connection with the free end of said coupling plate forming a closure for the compartment of said casing; a further object being 10 to provide means for retaining articles in and against displacement from said cover, said coupling plate serving to retain articles against displacement from the chamber of said casing; a further object being to provide means in one side wall of the casing cooperating with an adjacent side wall of said cover for retaining the cover against displacement from the casing and whereby the actuation thereof will release said cover; a further object being to provide means for automatically moving the cover into open position when released; a still further object being to provide means for coupling the separate end portions of a belt with said casing; and with these and other objects in view the invention consists in a device of the class and for the purpose specified which is simple in construction, efficient in use, and which is 15 constructed as herein described and claimed.

The invention is fully disclosed in the following specification, of which the accompanying drawing forms a part, in which the separate parts of my improvement are designated by suitable reference characters in 20 each of the views, and in which:

Fig. 1 is a perspective view of a belt showing the buckle arranged thereon.

Fig. 2 is a partial section on the line 2—2 45 of Fig. 1 on an enlarged scale.

Fig. 3 is a section on the line 3—3 of Fig. 1 on an enlarged scale.

Fig. 4 is a perspective view of the buckle detached, showing the parts in an open position.

Fig. 5 is a section on the line 5—5 of Fig. 3; and,

Fig. 6 is a rear elevation of the buckle detached.

In carrying my invention into effect, I 55 provide a buckle casing 10 having a central box-shaped portion 11 forming a chamber or compartment 13 opening outwardly through said casing, the side walls of the casing 11 extending at the front thereof to form front plates 12 disposed at opposite sides of the chamber 13 in said casing, and these plates have top and bottom flanges 14 arranged in alinement with the top and bottom walls of the casing and soldered or otherwise secured 65 thereto.

One of the plates 12 terminates at its free side edge in a downwardly and inwardly extending tongue 15 disposed within the side walls 14, and in connection with which an apertured coupling plate 16 at one end of the belt 17 is adapted to operate, the other end of said belt being secured within and to the plate 12 by a V-shaped clamp plate 18 pivoted to the side walls 14, as seen at 19, 75 having a tooth-like edge 20 adapted to engage the belt as in other devices of this class.

For the purpose of description, the walls 10a of the casing will be regarded as the top wall, and the wall 10b the bottom wall and 80 10c will represent the side walls of the box-shaped portion 11. Mounted in the side walls 10c and adjacent the top wall 10a is a hinge pin 21, which pin is arranged within the chamber 13 and mounted on said pin is a coupling plate or link 22 to permit the swinging movement of said plate with respect to the casing, the free end of the plate terminating in a cylindrical knuckle 23 through which a hinge pin 24 is passed, said pin also passing 85 through other knuckles 25 disposed at opposite sides of one end wall 26 of a closure cap or cover 27, the other end wall 28 having an aperture 29 centrally thereof. The cap 27 also includes side walls 30 forming a chamber or compartment within the cap, and a plate member 31 is employed for retaining articles within said chamber, which is designated by the reference character 27a.

The member 31 is substantially U-shaped 100

in form and terminates in spring members 32 disposed at opposite sides thereof, and which normally extend below the lower edges of the side walls 30 of the cap. The member 31 includes a depending end wall 31a which rests upon the inner surface of the top wall of the cap 27 and is secured to said wall and the side walls 30, and my invention is not necessarily limited to the specific manner of forming and arranging the member 31.

Supported in connection with the top wall 10a of the casing is a latch member 33 consisting of an arc-shaped spring plate 34 disposed in the chamber 13 of the casing, normally bearing upon the hinged end 22a of the plate 22 and has centrally thereof, a tongue or lip 35 adapted to cooperate with the aperture 29 in the wall 28 of the cap 27 to hold said cap against displacement from the casing as clearly seen in Fig. 3 of the drawing. The central portion of the latch 33 has an outwardly directed catch button 36 which passes and projects through an aperture in the top wall 10a of the casing, and by means of which the latch may be moved into inoperative position against the tension of the spring plate 34 to release the cover 27, which cover is automatically moved into open position, as indicated in dotted lines in Fig. 3 of the drawing, by the spring members 32 which normally bear upon the plate 22 under tension as seen in said figure.

The plate 22 is held against displacement from the casing by the spring 34, and the engagement of the spring with the cylindrical end 22a retains the latch in position, the assemblage of these parts being made by first inserting the latch into position in the end wall 10a thereafter coupling the plate 22 with the casing by passing the pin 21 through the casing and the cylindrical end 22a of said plate, maintaining the spring 34 under tension in this operation.

It will be noted that the end of the pin 24 is adapted to engage the inner faces of the side walls 10c of the casing so as to frictionally retain the plate 22 in position, thus permitting the opening of the cover 27 without removing the plate 22 from the casing, and also permitting the movement of the plate into open position, as seen in Fig. 4, so as to acquire access to the bottom of the chamber 13.

It will be understood that my improved buckle may be used in connection with belts of various kinds and classes for both men, women and children, and the chambers 13 and 27a formed within and between the several parts of the buckle may be used for the storage of articles of merchandise, or other articles of any kind or class.

In the accompanying drawing, the buckle has been designed primarily for use in storing coins, paper money and similar articles, the coins being stored in the chamber 27a and

held in position therein by the member 31, thus forming a change pocket which is accessible when the cover 27 is moved into open position, whereas bills and other articles may be stored in the chamber 13 and held in position by the plate 22.

It will be understood that while I have shown certain details of construction for carrying my invention into effect, I am not necessarily limited to these details nor to any particular use of the invention, and various changes in and modifications of the construction herein shown and described may be made, within the scope of the appended claims, without departing from the spirit of my invention or sacrificing its advantages.

Having fully described my invention, what I claim as new and desire to secure by Letters Patent, is:—

1. A buckle of the class described comprising a casing, a chamber formed in said casing and opening through one side wall thereof, a closure member for said chamber, and means for coupling said closure member with the casing to permit the movement of the entire structure thereof relatively to said casing in opening and closing said chamber, said means comprising a coupling element pivotally supported within the chamber of said casing and to the free end of which the closure member is pivoted.

2. A buckle of the class described comprising a casing, a chamber formed in said casing and opening through one side wall thereof, a closure member for said chamber, means for coupling said closure member with the casing to permit the movement of the entire structure thereof relatively to said casing in opening and closing said chamber, said means comprising a coupling element pivotally supported within the chamber of said casing and to the free end of which the closure member is pivoted, and means forming a compartment within said closure member.

3. A buckle of the class described comprising a casing, a chamber formed in said casing and opening through one side wall thereof, a closure member for said chamber, means for coupling said closure member with the casing to permit the movement of the entire structure thereof, relatively to said casing, in opening and closing said chamber, said means comprising a coupling element pivotally supported within the chamber of said casing and to the free end of which the closure member is pivoted, means forming a compartment within said closure member, and a latch device on one side wall of said casing cooperating with said closure member to retain the same against displacement from the casing.

4. A buckle of the class described comprising a casing, a chamber formed in said casing and opening through one side wall thereof, a closure member for said chamber, means

for coupling said closure member with the casing to permit the movement of the entire structure thereof, relatively to said casing, in opening and closing said chamber, said

5 means comprising a coupling element pivotally supported within the chamber of said casing and to the free end of which the closure member is pivoted, means forming a compartment within said closure member, a latch device on one side wall of said casing cooperating with said closure member to retain the same against displacement from the casing, and said last named means comprising a spring element for automatically moving the closure member into open position when released by said latch.

5. A buckle of the class described comprising a casing, a chamber formed in said casing and opening through one side wall thereof, a closure member for said chamber, means for coupling said closure member with the casing to permit the movement of the entire structure thereof, relatively to said casing, in opening and closing said chamber, said means 20 comprising a coupling element pivotally supported within the chamber of said casing and to the free end of which the closure member is pivoted, means forming a compartment within said closure member, a latch device on one side wall of said casing cooperating with said closure member to retain the same against displacement from the casing, said last named means comprising a spring element for automatically moving the closure member into open position when released by said latch, and said latch comprising springs 25 cooperating with said coupling element to retain the same against displacement from said casing.

6. A compartment buckle of the class described comprising a main buckle part and a cover part for closing the compartment in said buckle part, means forming a supplemental compartment within said cover part, means for movably coupling the cover part with the main buckle part, means in one side wall of the buckle part cooperating with an adjacent side wall of the cover part for securing said cover part in closed position, and 45 said coupling means comprising a member pivotally supported within the chamber of the buckle part and movable into and out of said chamber.

7. A compartment buckle of the class described comprising a main buckle part and a cover part for closing the compartment in said buckle part, means forming a supplemental compartment within said cover part, means for movably coupling the cover part with the main buckle part, means in one side wall of the buckle part cooperating with an adjacent side wall of the cover part for securing said cover part in closed position, said coupling means comprising a member pivotally supported within the chamber of the 55

buckle part and movable into and out of said chamber, and tensional means for moving the cover part into open position when released from the buckle.

8. A buckle of the class described comprising a substantially box-shaped casing, the compartment of which opens outwardly through one side face thereof, a coupling plate pivotally supported in said casing adjacent one end thereof and adapted to be arranged within said chamber, a box-shaped cover hinged to the free end of said coupling plate and forming a closure for the open end of said chamber, and means forming a compartment within said cover.

9. A buckle of the class described comprising a substantially box-shaped casing, the compartment of which opens outwardly through one side face thereof, a coupling plate pivotally supported in said casing adjacent one end thereof and adapted to be arranged within said chamber, a box-shaped cover hinged to the free end of said coupling plate and forming a closure for the open end of said chamber, means forming a compartment within said cover, and means comprising a spring latch supported in one end of the buckle casing for retaining said cover in closed position.

In testimony that I claim the foregoing as my invention I have signed my name this 2nd day of Sept. 1930.

DAVIS MARINSKY.
